SPECTACLE STRAP OR CLIP

John R. Kerry, Grayslake, Ill., assignor to Bel-gard-Spero, Inc., Chicago, Ill., a corporation of Delaware

Application February 16, 1934, Serial No. 711,596

3 Claims. (Cl. 88—47)

This invention relates to a spectacle strap or clip.

A primary object of the invention is to provide an improved strap or clip which is sturdy and simple in construction. A further object is to provide a method of forming a strap with substantial saving in time and material, while yet providing a sturdy and serviceable product. Other specific objects and advantages will appear as the specification proceeds.

The invention is illustrated, in its preferred embodiments, by the accompanying drawing, in which—

Figure 1 is a part sectional view showing a strap embodying my invention, the section being taken as indicated at line 1 of Fig. 3; Fig. 2, a broken face view of a portion of a lens; Fig. 3, a sectional view, the section being taken as indicated at line 3 of Fig. 1; Fig. 4, a view similar to Fig. 1 of a modified form of the invention; Fig. 5, a view similar to Fig. 4 of a modified form of the invention; Fig. 6, a side view of a modified form of strap embodying my invention; Fig. 7, a sectional view of the strap shown in Fig. 6, the section being taken as indicated at line 7 of Fig. 6; and Fig. 8, a sectional view of another modified form of strap.

In the illustration given in Figs. 1 to 3 inclusive, 10 designates the arm of the strap having a slotted connection portion 11. The illustration shows the strap fastened to an arm commonly known as an end-piece. The strap or clip will also be attached to the bridge or center of the rimless mounting. The arm 10 is secured by solder or 30 other means to the U-shaped member 12.

The U-shaped member 12 preferably comprises two arc-shaped sides 13 connected at their rear by an integral rear wall 14. The rear wall 14 may be slightly curved, as indicated in the illustration, or it may be substantially straight. Preferably, the shape of the wall 14 is designed to correspond to the shape with the edge portion of the lens contacting it. Secured to the inner surface of wall 14, is an anchor strip 15, provided at 40 its ends with forwardly turned attachment lugs 16.

The edge portion of the lens 17 adjacent the strip is preferably provided with spaced slots 18 adapted to receive the attachment projections 16. I also prefer to cut away a portion of the glass at 19 between the two slots to compensate for the 50 depth of the rear wall of the anchor member 15. This results in the formation of locking shoulders 20 at the outer corners of the slots 18, the

shoulders 20 being adapted to abut the outer sides of the anchor member 15.

Heretofore, straps have been provided with outwardly turned locking projections adapted to engage spaced slots in the lens. However, it has been the practice to form the projections by machine mechanism which presses the metal out of the rear wall of the U-shaped member. With such a construction, there is a tendency for the projections to yield at times when pressure is placed upon the lens so as to form a loose or weak connection. With the improved construction shown in Figs. 1 to 3, the locking shoulders 20 abut the ends of the rear wall of the anchoring member 15, and any lateral pressure is taken by the rear wall of this member rather than by the forwardly extending projections 16. At the same time, the rear wall of the anchor member 15 buttresses the wall 14 at the area where it is connected to the strap arm 10.

In the modification shown in Fig. 4, the rear wall of the U-shaped member is pressed inwardly to form a recess receiving the rear wall of member 15. The arm 10 is secured to the rearwardly turned wall 21 within the area where it is buttressed by the rear wall of member 15.

In the modification of Fig. 5, the rear wall 22 is slotted at 23 to receive the projections 16. The rear wall of the member 15 engages the rear wall 22 and may be secured thereto by solder or other suitable means. The strap arm 10 is soldered to the member 15. In this construction, it will be observed that the combined walls 15 and 22 overlap in the area where the connection with strap arm 10 is made.

It will be noted that in the construction shown in Figs. 1 to 5, that the anchor member 15 provides a second wall at the point where connection is made with strap arm 10. With this construction, the rear wall of the U-shaped member may be made thinner because of the overlap of the two walls at the point of junction with strap arm 10. In the former practice, where the metal was drawn from the surface of the rear wall of the U-shaped member, it was necessary to provide a heavy rear wall. In applicant's improved method, the rear wall may be thin because a reinforced wall is afforded by member 15 within an area near the center of the rear wall where strength is desired.

In the modification shown in Figs. 6 and 7, the arc-like face 13 has segments 24 struck inwardly to provide locking projections adapted to engage slots 18 of lens 17. The pierced side wall may then be covered by a plate 25 having engraving thereon

if desired. With this construction, the side walls 13 need not be very thick because the projections 24 utilize the entire thickness of the side wall.

In the illustration given in Fig. 8, segments 5 26 are struck from the rear wall 27 and a plate 28 is secured to the rear wall. Strap arm 10 may then be soldered to wall 28.

If desired, the reinforcing wall 28 and wall 25 might be omitted although I prefer to have them 10 present as reinforcement for the weakened wall abutting them.

In the operation of the clip, the lens having first been provided with spaced slots 18, is pressed against the U-shaped member so that the projections 16 are received within slots 18, cement 15 being applied to form a tight connection.

The foregoing detailed description has been given for clearness of understanding only, and no unnecessary limitations should be understood 20 therefrom, but the appended claims should be construed as broadly as permissible, in view of the prior art.

I claim:

1. In combination with a lens having a pair 25 of spaced slots extending inwardly from its peripheral edge, a U-shaped member having sides adapted to engage the sides of said lens and having its rear wall provided with spaced slots, an anchor strip having forwardly turned ends extending through said slots and having its rear 30 wall abutting and secured to the rear wall of said U-shaped member, a strap arm secured to the rear wall of said anchor strip, the projections of said strip being adapted to engage the slots of said lens, and cement between said projections and lens for securing said strap to said lens.

2. In combination with a lens having a pair of parallel spaced slots extending inwardly from its peripheral edge and having also a peripheral edge portion cut away between said slots to provide shoulders at the outer edge portions of said slots, a strap comprising an arm, a substantially U-shaped member secured to the arm, and an anchor piece secured to the inner wall of said U-shaped member and having forwardly extending parallel projections engaging the slots of said lens, the said shoulders of the lens engaging the outer ends of said anchor piece, said U-shaped member having its side flanges curved forwardly so as to provide its widest dimensions between said parallel projections, and cement between said 15 flanges and lens for securing said strap to said lens.

3. In combination with a lens having a pair of parallel spaced slots extending horizontally inward from its peripheral edge, a substantially 20 U-shaped member extending about said peripheral edge, a strap comprising an arm secured to said U-shaped member, a non-resilient anchor piece secured to the wall of said U-shaped member and having its ends parallel and projecting horizontally within the slots of said lens, said U-shaped member having its side flanges curved inwardly to provide sides having their widest dimensions between said parallel projections, and cement extending about said anchor piece and 25 said U-shaped member for securing said strap to said lens, said strap being held against horizontal displacement from said lens only by the adhesive qualities of said cement.

JOHN R. KERRY.
